Des. 208,119
Patented July 18, 1967

208,119

MOTION PICTURE CAMERA HOUSING

Lawrence R. Teeple, Jr., San Carlos, and Leonard N. Albrecht, Mill Valley, Calif., assignors to Beckman & Whitley, Inc., San Carlos, Calif., a corporation of Delaware

Filed Sept. 7, 1965, Ser. No. 86,874

Term of patent 14 years

(Cl. D61—1)

Fig. 1.

Fig. 2.

Fig. 3.

FIG. 1 is a view in side elevation of a motion picture camera housing embodying our design;

FIG. 2 is a top plan view of the housing shown in FIG. 1; and

FIG. 3 is a bottom plan view of the same.

The side of the housing opposite from that shown is identical and the front and rear sides of the housing are conventional.

We claim:

The ornamental design for a motion picture camera housing, substantially as shown and described.
